UNITED STATES PATENT OFFICE.

JOHN BERG, OF CHICAGO, ILLINOIS, ASSIGNOR TO METAL SPECIALTIES MANUFACTURING COMPANY, OF CHICAGO, ILLINOIS, A CORPORATION OF ILLINOIS.

IGNITION DEVICE.

1,094,051.

Specification of Letters Patent.

Patented Apr. 21, 1914.

Original application filed September 18, 1912, Serial No. 720,963. Divided and this application filed May 26, 1913. Serial No. 769,933.

To all whom it may concern:

Be it known that I, JOHN BERG, a citizen of the United States, residing at Chicago, in the county of Cook and State of Illinois, have invented a new and useful Improvement in Ignition Devices, of which the following is a specification.

The present invention relates particularly to electric ignition devices capable of being used for lighting cigars, or for analogous purposes.

The present application constitutes a division of my application Serial No. 720,963, filed September 18, 1912.

15 The primary object of the invention is to provide an improved ignition-device which can be constructed cheaply, which is durable in use, and which will perform its function without the use of an excessive amount 20 of current.

The invention is illustrated in its preferred embodiment in the accompanying drawing, in which—

Figure 1 represents a side elevational 25 view of the improved ignition-device and a mounting, or socket-structure, which can be used in connection with the ignition-device; Fig. 2, an enlarged face view of the ignition-device; Fig. 3, a section taken as 30 indicated at line 3 of Fig. 2; and Fig. 4, a section taken as indicated at line 4 of Fig. 2.

A represents the mounting or socket structure, for the ignition-device; and B, the improved ignition-device. The mounting 35 comprises an arm 1 carrying a socket 2; and a spring arm 3 insulatingly secured at 4 to the arm 1, the spring arm 3 serving as a contact member which co-acts with a contact member 5 which is secured to an insulatingly mounted central terminal 6 with 40 which the socket 2 is provided. The terminal 6 is in the form of a screw, whose head is disposed within the bottom of the socket 2 in such position as to make contact 45 with the central terminal of the burner B. The socket 2 is of metal and is in electrical connection with the arm 1.

The mounting A is designed to be contained in a hollow handle; and the rear ends 50 of the arms 1 and 3 are adapted to be connected with electrical conductors (not shown).

The device B preferably comprises a metallic cup 7 having its base-portion 7^a fitted

with an externally-threaded tubular shank 5 7^b adapted to screw into the socket 2; insulating material 8 filling the tubular shank 7^b and partially filling the cup 7; a central post or conductor 9 whose lower end projects slightly below the shank 7^b and affords a 10 central terminal adapted to contact with the central terminal 6 of the socket 2; an outer post 10 rising from the base-portion of the cup 7, with which it is in electrical connection; a resistance coil 11 of convolute form 15 having its inner end attached to the central post and having its outer end attached to the post 10; a perforate disk 12, of mica, or the like, disposed above the resistance coil; and a washer or retainer-ring 13 serving to hold 20 the mica-disk in place.

The post 9 is struck laterally or kinked at an intermediate point, as indicated at 9^a, and said post is embedded in the insulating material 8, which is usually introduced 25 while in plastic form, becoming "set" after such introduction. Thus, the post 9 is securely embedded in the insulating material. The post 10 is fixed in the bottom 7^a of the cup, and is also embedded in the insulating 30 material. The upper ends of the posts project slightly above the insulating material, and the posts are provided with bores or sockets adapted to receive the downwardly or inwardly turned extremities of the resistance coil 11. The ends of the coil are secured in the sockets in the posts by means 35 of the wedging pins 14 and 15. Before the insulating material 8 becomes hard, it is preferred to embed therein radially-disposed mica strips 16 whose upper edges project somewhat above the outer surface of the material 8 and serve to support the convolutions of the resistance coil. It will be noted that a small air-space 17 is thus provided 40 below the resistance coil so that it will be unnecessary to heat the material 8 when the device is being used for cigar-lighting purposes. The mica strips, while very thin, are sufficiently tenacious to avoid chipping. 45 On the other hand, the light resistance coil, which is usually rather fragile, is well supported and is closely confined between the edges of the radial strips 16 and the superposed mica disk 12. The mica disk is provided, in the usual manner, with perforations 18.

It will be noted that when the device B

is connected with the socket 2, the metal shank 7^b of the cup contacts with the metal socket 2, while the central terminal 9 contacts with the central terminal 6 of the 5 socket.

The circuit may be closed by pressing the spring arm 3 against the contact member 5. Means for accomplishing such purpose are usually provided in an organized cigar- 10 lighter, such means being mounted on the handle in which the socket-structure A is housed.

The foregoing detailed description has been given for clearness of understanding, 15 and no unnecessary limitations should be understood therefrom.

What I regard as new and desire to secure by Letters Patent is—

1. In a device of the character set forth, 20 an igniter comprising a cup-shaped member equipped with a tubular threaded shank, an insulating composition in said shank and the bottom portion of said cup, a central post extending through said insulating composition, an outer post rising from and having permanent electrical connection with the bottom of said cup and extending through said insulating composition, a resistance coil having its inner end connected 25 with said central post and its outer end connected with said outer post, and a protecting covering over said resistance coil.

2. In a device of the character set forth, 30 an igniter comprising a cup equipped with a threaded tubular shank, an insulating composition filling said shank and the lower portion of said cup, separately formed thin insulating strips embedded in said composition and projecting above the upper surface 35 thereof, a central post extending through said composition, an outer post extending through said composition and having per-

manent electrical connection with the bottom of said cup, a resistance coil having its inner end connected with said central post 45 and its outer end with said outer post, said resistance coil resting on the upper edge portions of said insulating strips, and a perforate protecting insulating cover above said resistance coil. 50

3. In a device of the character set forth, 55 an igniter comprising a cup equipped with a threaded tubular shank, an insulating composition in said shank and the bottom portion of said cup, separately formed thin insulating strips embedded in said composition and projecting above the upper surface thereof, a central post extending through said composition, and having an offset or roughened surface within the composition, an outer post extending through said composition and in permanent electrical connection with said cup, a resistance coil having its inner end connected with said central post and its outer end connected with 60 said outer post, said resistance coil resting on the upper edge portions of said insulating strips, and a protecting cover within said cup above said resistance-coil: 65

4. An igniter of the character set forth, 70 comprising a cup having a tubular shank, an insulating composition in said shank and the bottom portion of said cup, a central post extending through said composition, thin insulating strips embedded in said composition and projecting above the surface thereof, and a resistance coil having its inner end secured to said post and having its outer end electrically connected with said cup. 75

JOHN BERG.
